CIRCUIT INTERRUPTER

Thomas E. Curtis and Harlow E. Lichtwardt,
 Hampton, Ga., assignors to Southern States
 Equipment Corporation, a corporation of
 Georgia

Application April 6, 1953, Serial No. 347,122

16 Claims. (Cl. 200—114)

1

This invention relates to circuit interrupters and more particularly to interrupters of the type commonly referred to as load break cutouts or fuses.

Electric cutouts which incorporate a fusible element disposed within a fuse tube of insulating material are adapted for interrupting over-load or fault currents by expulsion action in response to the melting of the fusible element and, if desired, load currents may be interrupted by physically breaking the fusible element thereby to draw an arc within the fuse tube which is extinguished by expulsion action in known manner. The circuit interrupting action may be accompanied by withdrawal of one end of the fusible element from the fuse tube by means of an ejector element constructed of a low mass and provided with biasing means arranged to effect a rapid withdrawal of the fuse link from the fuse tube.

Power fuses and cutouts which are provided with a pair of contacts respectively mounted at each end of the fuse tube and interconnected by a fusible element disposed within the tube are arranged so that the contacts are respectively engageable with a pair of spaced terminals forming a part of the circuit protected by the fuse or cutout. When the fusible element is ruptured due either to fault or overload current or to the application of a physical force thereto, the arc drawn must be extinguished before the cutout or fuse drops out; i. e., before one of the contacts on the fuse tube separates from its associated terminal in order to prevent the drawing of an arc between such contact and terminal.

A principal object of this invention is the provision of an improved load break cutout which is simple in construction and which is characterized by a high degree of uniformity of operation whether interrupting its controlled circuit under fault or normal load conditions.

Another object of this invention is to provide an improved ejector arrangement for use in conjunction with load break fuses or cutouts.

Still another object of this invention is the provision of an improved load break fuse or cutout which is arranged to afford ample opportunity for extinguishment of an arc drawn within the fuse tube before the device drops out to establish in known manner a wide gap in the controlled circuit and to relieve the device of severe voltage stresses.

The invention in one form as applied to a load break cutout comprises a conducting element pivotally supported by a fuse tube, an

2

ejector element pivotally mounted on the conducting element, a fusible element arranged so as normally to maintain the conducting and ejector elements in their normal positions, and handle means for moving the conducting and ejector elements out of their normal positions thereby to break the fusible element and allow the ejector element promptly to withdraw one end of the fusible element from the fuse tube. In accordance with one feature of the invention the conducting element is arranged with respect to the fuse tube and to the fixed terminal structure so that sufficient relative motion of the parts takes place to break the fusible element before substantial axial movement of the tube is effected. Thus an arc drawn within the fuse tube is extinguished before one of the contacts separates from its associated terminal.

For a better understanding of the invention reference may be had to the following description taken in conjunction with the accompanying drawings in which Fig. 1 is a side view of a load break cutout embodying the invention, Fig. 2 is an enlarged side view partially in section of a portion of the structure shown in Fig. 1, and in which Fig. 3 is a detailed view of a portion of Figs. 1 and 2.

With reference to Fig. 1 the numeral 1 represents a support arm which at its left-hand end is mounted on a supporting structure (not shown) and which at its right-hand end is secured to insulators 2 and 3. Affixed to the upper end of insulator 2 is a terminal element 4 which is provided with openings 5 and 6 for cooperating with a longitudinally split bolt 7 by which a conductor (not shown) may be secured to the terminal 4. Also formed in the terminal 4 is an opening 8 which may be used in any desired manner to facilitate mounting of the device or the dismantling thereof. A hood 9 is pivoted at 10 to the terminal 4 for limited rotary movement and is provided with a latching surface 11. A brush contact 12 is also secured to the terminal 4. Latch 11 and contact 12 cooperate with the movable fuse assembly generally designated by the numeral 13 in a manner to be more specifically described hereinafter.

A terminal 14 is affixed to the lower end of insulator 3 and is provided with a slot 15 which, as shown in Fig. 1, receives one portion of the longitudinally split terminal bolt 16 for connecting the terminal 14 with a circuit conductor (not shown). Terminal 14 is also provided with a pair of spaced extensions 14a between which the contact brush 17 is mounted. The spaced exten-

sions 14a of the terminal element 14 are provided with jaws 18 which cooperate with portions of the fuse assembly 13 in a manner to be described hereinafter.

The fuse assembly 13 comprises a contact element 19 which is provided with a contacting surface 20 for cooperating with the contact brush 12 and is also provided with an upwardly extending latching portion 21 which as indicated in Fig. 1 is engageable with the latching surface 11 of the contact hood 9. Secured to the upper end of the contact 19 is a cap member 22. If desired, cap member 22 and contact member 19 may be constructed in accordance with the disclosure of application Serial No. 338,836 filed February 25, 1953, by Thomas E. Curtis and James M. deMontmollin and assigned to the assignee of this invention. It will be understood that insofar as the principles of this invention are concerned any known assembly arrangement could be used instead of the above referred to structure generally designated by the numeral 19 in Fig. 1. As is well known in the art, a fusible element is disposed within the fuse tube 23 and is secured to the contact 19 at its upper end and provided with a projecting portion 24 which extends out of the lower end of the fuse tube 23.

Affixed to the fuse tube 23 by means of the screw 25 is a terminal element 26 which is provided with an opening 27 therein for receiving a switch stick or other operating member. Terminal element 26 is also provided with a pivotal mounting 28 for the conducting element 29 which is provided with a contacting surface 30 for cooperating with the brush contact 17. The conducting element 29 is also provided with a shoulder 31 which engages a portion 32 formed in the left-hand extremity of the terminal element 26. Normally the shoulder 31 of the conducting element 29 engages the projection 32 of the terminal element 26 as is indicated in Fig. 1. Also formed integrally with the conducting element 29 is a pair of trunnions 33 which respectively engage the jaws 18 formed in the extensions 14a of the terminal element 14, the jaws 18 and trunnions 33 constituting a fixed pivot.

Pivottally mounted at 34 on the conducting element 29 is the ejector element 35. The pivot 34 for the ejector 35 coincides with the center of rotation of the trunnions 33. Ejector 35 is provided with an upwardly extending portion 36 which is arranged to engage a projection 37 formed in the conducting element 29. Thus counterclockwise rotation of ejector element 35 about its pivot 34 is prevented when the upwardly extending shoulder portion 36 engages the projecting portion 37 of conducting element 29. Ejector element 35 is biased for rotation in the clockwise direction about its center of rotation 34 by means of the coiled spring 38. Also mounted by a threaded engagement on the conducting element 29 is the connector means 39 which secures the end of the conductor 24 in position on the conducting element 29 as best shown in Fig. 2. Thus by means of the fusible element and the extension 24 thereof the conducting element 29 and ejector element 35 are maintained in their normal or solid line positions as indicated in Fig. 1 so that normally a circuit is complete through the device. Such a circuit comprises the terminal 14, the brush contact 17, conducting element 29, fusible element 24, contact 19, the brush contact 12, and the terminal 4.

Upon the occurrence of a fault or overload

condition on the circuit controlled by the device, the fusible element disposed within the fuse tube 23 melts and the ejector 35 promptly withdraws the conductor 24 and parts associated therewith from the lower end of the fuse tube 23. The arc drawn within the fuse tube 23 is extinguished by expulsion action in known manner. During this period the pivot 28 moves from the position indicated by the numeral 28 to the position indicated in Fig. 2 by the numeral 28' due to the weight of the structure 13 and to the biasing action of the brush contact 17. Continued rotation of pivot 28 about the trunnions 33 as a center eventually causes downward motion of the upwardly projecting portion 21 of the contact 19 thereby to disengage latching surface 11. Thereafter the whole structure 13 swings in a clockwise direction about the trunnions 33. In this way an isolating gap is established between the terminals 4 and 14.

The arrangement above described is also adaptable for use as a device for interrupting normal load current; i. e., current which is insufficient in magnitude to melt the fusible element. In this connection it will be observed that the conducting element 29 is provided with a manually operable handle 40 which at its right-hand extremity is provided with an opening 41 for receiving the laterally projecting portion 42 of a switch stick 43. Thus with the parts occupying the positions shown in Fig. 1 a downward pull on the switch stick 43 causes the pivot 28 to move in a clockwise direction about the center 33. Since the shoulder 36 of the ejector 35 is in engagement with the stop 37 on conducting element 29, the ejector 35 cannot rotate in a counterclockwise direction about its center 34. Thus a tension force is applied to the conductor 24 which is sufficient to break the fusible element disposed within the fuse tube 23. Upon rupture of this element an arc is drawn and subsequently extinguished by expulsion action in known manner. From Fig. 1 it will be observed that the axis of tube 23 is spaced closer to the center of rotation comprising the trunnions 33 when the parts are in their normal position than is the pivot 28 and that the lower end of tube 23 is normally closer to fixed pivot 33 than to the pivot 28. Thus substantial arcuate movement of pivot 28 through dead center and beyond with respect to the pivot 33 can be effected along with transverse movement to the right of tube 23 before any appreciable movement of the tube 23 in an axial direction thereof takes place. For this reason the latching surface 11 snugly engages and securely holds the projecting portion 21 of the contact 19 in a contact-making position until ample opportunity has been afforded to rupture the fusible element within tube 23 and to extinguish the arc drawn therein. Thus destructive arcs between contact surface 20 and brush contact 12 are prevented.

It will be observed that whether the conducting element 29 occupies the position shown in Fig. 1 or whether the ejector element and conducting element 29 have been moved to the position indicated in Fig. 2, the biasing action of spring 38 tending to rotate the ejector element 35 is the same. Thus substantially uniform ejecting action is accomplished whether the device is being operated as an overload or fault responsive device or whether the device is being operated as a load break device.

While we have shown and described a particular embodiment of the invention, we do not

wish to be limited thereto and intend in the appended claims to cover all such changes and modifications as fall within the true spirit and scope of the invention.

What we claim as new and desire to secure by Letters Patent of the United States is:

1. An electric fuse comprising a fuse tube, a fusible element secured within said tube and having a portion thereof extending out of one end of said tube, a conducting element movably supported by said tube and having a normal position with respect thereto, an ejector element movably supported by said conducting element and having a normal position with respect thereto from which said ejector is movable in only one direction, said portion of said fusible element being normally interrelated with said ejector element so as to hold said ejector element in its normal position relative to said conducting element, and manual means for moving said conducting element out of its normal position without moving said ejector element relative to said conducting element thereby physically to break said fusible element.

2. An electric fuse comprising a fuse tube, a fusible element securely mounted within said tube and having a portion thereof extending out of one end of said tube, a conducting element movably supported by said tube and having a normal position with respect thereto, an ejector element movably supported by said conducting element and having a normal position with respect thereto from which said ejector is movable in only one direction, said portion of said fusible element being normally interrelated with said ejector element so as to hold said ejector element in its normal position relative to said conducting element, and a handle movable with said conducting element for applying a force thereto sufficient to break said fusible element.

3. An electric fuse comprising a fuse tube, a fuse link having a first portion thereof securely affixed within said tube and having a second portion thereof extending out of one end of said tube, a conducting element movably supported by said tube and having a normal position with respect thereto, an ejector element movably supported by said conducting element and having a normal position with respect thereto from which said ejector is movable in only one direction, said second portion of said fuse link being normally interrelated with said conducting and ejector elements so as to hold said conducting and ejector elements in their normal positions, and manual means for moving said conducting element out of its normal position without moving said ejector element relative to said conducting element thereby physically to break said fuse link.

4. An electric fuse comprising a fuse tube, a fuse link having a first portion thereof securely affixed within said tube and having a second portion thereof extending out of one end of said tube, a conducting element movably supported by said tube and having a normal position with respect thereto, an ejector element movably supported by said conducting element and having a normal position in engagement with a part of said conducting element thereby to prevent movement of said ejector element relative to said conducting element in one direction, biasing means tending to move said ejector element in another direction out of its normal position, connector means for securing said second portion of said fuse link to said conducting element so as to maintain said conducting element in its normal

position, said second portion of said fuse link normally being in engagement with said ejector element so as normally to hold said ejector element in its normal position relative to said conducting element, and manual means for moving said conducting element out of its normal position without moving said ejector element relative to said conducting element thereby physically to break said fuse link.

5. An electric fuse comprising a fuse tube, a fusible element disposed within said tube and having one end thereof secured therein and having the other end thereof extending out of one end of said tube, a conducting element secured by pivotal support means to said tube and having a normal position with respect to said tube, an ejector element pivotally supported by said conducting element and having a normal position with respect thereto, said ejector element having a shoulder engageable with a portion of said conducting element to prevent rotation thereof in one direction from its normal position, connector means for securing said other end of said fusible element to said conducting element thereby to hold said conducting and ejector elements in their normal positions, and manual means operably related with said conducting element for moving said conducting element out of its normal position without moving said ejector element relative to said conducting element thereby physically to break said fusible element.

6. An electric fuse comprising a fuse tube, a fusible element disposed within said tube and having a portion thereof extending out of one end of said tube, a conducting element secured by a pivot means to said tube and having a normal position with respect to said tube, a fixed pivot about which said conducting element is rotatable, said portion of said fusible element being interrelated with said conducting element so as normally to hold said conducting element in its normal position, said pivots being normally disposed with respect to said tube so that predetermined movement of said conducting element about said pivots imparts substantial transverse movement to said tube in a direction away from said fixed pivot before causing substantial axial movement thereof.

7. An electric fuse comprising a fuse tube, a fusible element having one end thereof secured within said tube and having a portion thereof extending out of one end of said tube, a conducting element secured by a pivot means to said tube and having a normal position with respect to said tube, a fixed pivot about which said conducting element is rotatable, said portion of said fusible element being interrelated with said conducting element so as normally to hold said conducting element in its normal position, said pivots being normally disposed with respect to said tube so that predetermined movement of said conducting element about said pivots imparts substantial transverse movement to said tube before causing substantial axial movement thereof, and manually operable means for imparting operating movement to said conducting element.

8. An electric fuse comprising a fuse tube, a fusible element disposed within said tube and having a portion thereof extending out of one end of said tube, a conducting element secured by a first pivot means to said tube and having a normal position with respect to said tube, a fixed pivot about which said conducting element is rotatable, said portion of said fusible element being interrelated with said conducting element so as

normally to hold said conducting element in its normal position, said fixed pivot being closer to the axis of said tube and to said one end thereof than said first pivot when said conducting element is in its normal position so that predetermined movement of said conducting element about said pivots imparts substantial transverse movement to said tube before causing substantial axial movement thereof.

9. An electric fuse comprising a fuse tube, a fusible element disposed within said tube and having a portion thereof extending out of one end of said tube, a conducting element secured by a first pivot means to said tube and having a normal position with respect to said tube, a fixed pivot about which said conducting element is rotatable, said portion of said fusible element being interrelated with said conducting element so as normally to hold said conducting element in its normal position, said fixed pivot being closer to the axis of said tube and to said one end thereof than said first pivot when said conducting element is in its normal position so that predetermined movement of said conducting element about said pivots imparts substantial transverse movement to said tube before causing substantial axial movement thereof, and manually operable means for imparting operating movement to said conducting element.

10. An electric fuse comprising a fuse tube, a fusible element having one end thereof secured within said tube and having a portion thereof extending out of one end of said tube, a conducting element secured by a first pivot means to said tube and having a normal position with respect to said tube, a fixed pivot about which said conducting element is rotatable, connector means for securing said portion of said fusible element to said conducting element so as to hold said conducting element in its normal position, said fixed pivot being closer to the axis of said tube and to said one end thereof than said first pivot when said conducting element is in its normal position, and a handle movable with said conducting element for simultaneously rotating said conducting element about said first and said fixed pivots so as to increase the distance between said fixed pivot and said tube thereby to break said fusible element.

11. An electric fuse comprising a fuse tube, a fusible element secured within said tube and having a portion thereof extending out of one end of said tube, a conducting element secured by a first pivot means to said tube and having a normal position with respect to said tube, a fixed pivot about which said conducting element is rotatable, connector means for securing said portion of said fusible element to said conducting element so as to hold said conducting element in its normal position, said fixed pivot being closer to the axis of said tube and to said one end thereof than said first pivot when said conducting element is in its normal position, and a handle movable with said conducting element for simultaneously rotating said conducting element about said first and said fixed pivots so as initially to increase the distance between said fixed pivot and said tube without imparting appreciable movement to said tube in a direction axially thereof thereby to break said fusible element.

12. An electric fuse comprising a fuse tube, a fusible element secured within said tube and having a portion thereof extending out of one end of said tube, a conducting element secured by a first pivot means to said tube and having a nor-

mal position with respect to said tube, a fixed pivot about which said conducting element is rotatable, an ejector element movably supported by said conducting element and having a normal position with respect thereto from which said ejector element is movable in only one direction, said portion of said fusible element being normally interrelated with said conducting and ejector elements so as to hold said conducting and ejector elements in their normal positions, said pivots being normally disposed with respect to said tube so that simultaneous movement of said conducting element about said pivots imparts substantial transverse movement to said tube before causing substantial axial movement thereof, and a handle movable with said conducting element for simultaneously rotating said conducting element about said first and said fixed pivots so as to change the distance between said fixed pivot and said tube thereby to break said fusible element.

13. An electric fuse comprising a fuse tube, a fusible element secured within said tube and having a portion thereof extending out of one end of said tube, a conducting element secured by a first pivot means to said tube and having a normal position with respect to said tube, a fixed pivot about which said conducting element is rotatable, an ejector element movably supported by said conducting element and having a normal position with respect thereto from which said ejector is movable in only one direction, said portion of said fusible element being normally interrelated with said conducting and ejector elements so as to hold said conducting and ejector elements in their normal positions, said fixed pivot being closer to the axis of said tube than said first pivot and said pivots being spaced from each other in a direction longitudinally of said tube with said fixed pivot nearer said one end of said tube when said conducting element is in its normal position, and a handle movable with said conducting element for simultaneously rotating said conducting element about said first and said fixed pivots so as initially to increase the distance between said fixed pivot and said tube without imparting appreciable movement to said tube in a direction axially thereof thereby to break said fusible element.

14. An electric fuse comprising a fuse tube, a fusible element secured within said tube and having a portion thereof extending out of one end of said tube, a conducting element secured by a first pivot means to said tube and having a normal position with respect to said tube, a fixed pivot about which said conducting element is rotatable, an ejector element movably supported by said conducting element and having a normal position with respect to said conducting element, connector means for securing said portion of said fusible element to said conducting element so as to hold said conducting element in its normal position, said portion of said fusible element normally being in engagement with said ejector element so as normally to hold said ejector element in its normal position relative to said conducting element, one of said pivots normally being closer to the axis of said tube than the other of said pivots and said pivots normally being disposed longitudinally of said tube so that simultaneous predetermined movement of said conducting member about said pivots causes transverse movement of said tube before causing appreciable axial movement thereof, and a handle movable with said conducting element for simul-

taneously rotating said conducting element about said first and said fixed pivots so as to change the distance between said tube and one of said pivots thereby to break said fusible element.

15. An electric fuse comprising a fuse tube, a fusible element secured within said tube and having a portion thereof extending out of one end of said tube, a conducting element secured by a first pivot means to said tube and having a normal position with respect to said tube, a fixed pivot about which said conducting element is rotatable, an ejector element movably supported by said conducting element and having a normal position with respect thereto, connector means for securing said portion of said fusible element to said conducting element so as to hold said conducting element in its normal position, said portion of said fusible element normally being in engagement with said ejector element so as normally to hold said ejector element in its normal position relative to said conducting element, said fixed pivot normally being closer to the axis of said tube than said first pivot and said pivots being spaced from each other in a direction longitudinally of said tube when said conducting element is in its normal position, and a handle movable with said conducting element for simultaneously rotating said conducting element about said first and said fixed pivots so as initially to increase the distance between said fixed pivot and said tube without imparting appreciable movement to said tube in a direction axially thereof thereby to break said fusible element.

16. A circuit interrupter comprising a tube of insulating material, a fusible element secured 35

within said tube and having a portion thereof extending out of one end of said tube for interrupting an electric current therethrough by expulsion action, a terminal element affixed to said tube, a conducting element secured to said terminal element by a first pivot, said conducting element being engageable with a portion of said terminal element to prevent rotation thereof in one direction, said conducting element also being rotatable about a fixed pivot, an ejector element pivotally supported by said conducting element and biased for rotation relative to said conducting element in one direction, said ejector element being engageable with a portion of said conducting element so as to prevent rotation of said ejector in the other direction, means for securing one end of said fusible element to said conducting element so as normally to maintain said ejector in engagement with said conducting element and to hold said conducting element in engagement with said terminal element, said fixed pivot normally being closer to the axis of said tube and to said one end thereof than said first pivot, and manual means for rotating said conducting element about its fixed and first pivots thereby to break said fusible element and establish an arc to be interrupted within said tube.
